UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

COAL-MINING MACHINE.

Application filed June 26, 1925. Serial No. 39,857.

This invention relates to coal mining machines of the bottom cutting type and more particularly to the feeding means therefor.

In the undercutting of coal in seams which are steeply inclined, it is the common practice to move the cutting mechanism up the pitch during insertion of the cut, it being found that this is the better method for a number of reasons. During the insertion of such cuts the resistance to movement of the machine is of course substantially greater than during undercutting on the level, for not only must the resistance opposed by the coal be overcome, but in addition the weight of the machine is in part supported by the flexible feeding means. As a result the possibilities of breakage of the flexible feeding members employed in the traction of the machine during cutting is somewhat increased and it is therefore desirable to make some provision for the safety of the operator and of the machine in the event of the breakage of the flexible traction member. Even under the conditions which exist during cutting on the level the jacks are apt to slip and this possibility also gives rise to a need for additional safety provisions in cutting on a steep pitch. Finally, in the event that the motor is stopped while the machine is cutting up a steep pitch, it is possible with certain types of feed operating gearing for the weight of the machine to cause it to slip back down hill.

A principal object of the present invention is to provide safety means for preventing damage to a mining machine or injury to the operator due to failure, or interruption of operation from any cause, of the feeding means. More specifically, it is an object of the invention to provide a safety mechanism adapted to be associated with a mining machine for the purpose of providing an auxiliary flexible connection with a point in advance of the machine, together with means for controlling the length of said connection permitting the length of the connection to be freely varied as desired, but normally operative to shorten the connection in proportion to the shortening of the advance flexible feeding portion, and automatically operative to prevent lengthening of said connection, whereby failure of the feeding means will not result disastrously. Other objects and advantages of the invention will hereinafter more fully appear.

In a preferred form the invention may comprise a flexible connection to a point in advance of the machine frame together with rotatable means operatively engaging the connection and actuated by the feeding mechanism of the machine in such manner that the free length of the connection is varied in proportion to variations in the length of the advance flexible feeding member employed in effecting movement of the machine. Preferably the winding member takes the form of a drum and the connection the form of a cable adapted to be wound upon the drum and preferably the means for effecting shortening of the connection takes the form of actuating mechanism driven by cooperation with the advance flexible feeding portion of the machine. In a preferred form the mechanism comprises means automatically preventing the lengthening of the connection except when desired and comprises a friction controlled ratchet mechanism which is preferably of a character such that an operator may reverse the operation of the ratchet mechanism to adapt the mechanism to use on opposite sides of a mining machine when cutting in opposite directions.

In the accompanying drawings in which one illustrative embodiment of the invention is disclosed:

Fig. 1 is a plan view of a mining machine equipped with the illustrative form of my invention.

Fig. 2 is a side elevation of a mining machine so equipped.

Fig. 3 is a central vertical section on the line 3—3 of Fig. 2.

Fig. 4 is a horizontal section on the line 4—4 of Fig. 3.

Fig. 5 is an enlarged view of the pawl mechanism upon a plane corresponding to that of Fig. 4.

Referring to the drawings, a mining machine 1 having a power driven feed operating member 2 is fed by the cooperation of said feed operating member with a flexible feeding member 3 in the form of a chain extending from a guide sheave 4 at the forward end of the machine to a point in advance of the latter, the angle of the machine to the work being controlled by a receding portion 5 extending to a jack or takeup member (not shown) to the rear of the mining machine. The machine is adapted to

cut in opposite directions, a guide sheave 4^a corresponding to the sheave 4 being disposed at the forward end of the opposite side of the machine and sprockets 6 and 6^a being provided in duplicate at the rear end of the machine about which the chain 3 may pass between the feed sprocket 2 and the guide sheaves 4 and 4^a.

The safety device generally designated 10, 10 comprises an attaching or base plate 11 which may be bolted or otherwise securely mounted on either side of the machine frame 1 and between the ends of the latter. Adjacent its corners the plate 11 is provided 15 with attaching lugs; upper lugs 12 slotted to provide spaced pairs of lugs, and lower lugs 13. The several lugs are provided with openings through which heavy bolt members 14 may pass, and upper and lower end members 15, 16 respectively are held rigidly to the base plate 11 by the bolts 14. The end members 15 and 16 have aligned bores 17 and 18 in which grease bearing bushings 19 and 20 are respectively mounted. A shaft 22 is 25 journaled in the bushings 19 and 20 and a collar 23 thereon prevents downward longitudinal movement of the shaft. Keyed to the shaft 22 is a sleeve member 24 notched as at 25 at its upper end to permit the 30 clutching thereto of a member later described. A drum 26 is keyed at its lower end to the sleeve 24 and is adapted to constitute a winding member for the safety connection 27. Within an annular recess 28 35 between the upper end of the drum and the exterior of the sleeve 24 lies the sleeve-like bottom portion 29 of a ratchet member 30. The member 30, which is of larger diameter at its upper end than at its sleeve portion 40 29 is provided with an exterior braking surface 32 and with an internal set of ratchet teeth 33. Within the toothed portion of the member 30 is disposed an annular pawl carrier 34 whose lower portion has clutch teeth 45 35 engaging in the sockets 25 in the member 24. The pawl carrier accordingly rotates with the drum 26. In the periphery of the pawl carrier 34 are cut a series of approximately semi-circular recesses 36 in which 50 double pawl members 37 are oscillatably mounted. The recesses open through the inner wall of the member 34. Each of the pawls is of a shape formed by cutting off unequal segments of a circle to provide opposite parallel sides and then cutting away 55 the remaining material to leave at each outer corner a pawl or tooth portion adapted to interfit with the ratchet teeth. It will be evident that pressure applied to the arcuate 60 ends of the pawl members will be transmitted by them to the opposite ends of the recesses 36 and there will be very little tendency towards oscillation, while the tooth or pawl portions will readily slip over the 65 ratchet teeth on movement in the opposite

direction. The opposite sides of the pawl members 37 are recessed as at 38 for coaction with spring pressed follower pins. Within the bore 39 of the annular pawl carrier 34 is a ring 40 carrying radially disposed spring pressed follower pins 42 adapted to engage in the recesses 38. A handle 43 is mounted on the upper end of shaft 22 and may be securely held thereto by a screw 44. The handle has a sleeve portion 45 which enters a central opening in the ring 40 and is keyed to the latter. It will be evident that on loosening of the screw 44 the handle may be turned to move the ring 40 and with the latter the pins 42 so that the action of the pawls 37 will be reversed, and retightening of the screw will maintain the setting.

A brake band 46 having supporting lugs 47 disposed between the spaced lugs 12 and 13 traversed by the bolts or rods 14, is adapted to cooperate with the braking surface 32. The band is of the split type and carries at its ends ears 48 respectively pivotally connected to a threaded rod 49 and to a stirrup 50 within whose shank 51 the rod 49 is slidably mounted. The ears 48 lie within the loop of the stirrup. A hand wheel 52 carries a threaded nut 53 which coacts with the threaded rod 49 to tighten and loosen the 55 brake band. The rod 49 is secured to its associated ear 48 by a pin 55 whose extended ends slide in slots 56 in the stirrup member 50 to guide the parts. The end of the stirrup has an opening 57 therein to permit assembly.

At its lower end the shaft 22 has keyed thereto a driving member 54 whose periphery is grooved to cooperate with the feed chain. In the event that a cable or rope feed 105 were employed, the driving member could be replaced by a rope engaging member. The effective diameter or pitch diameter of the member 54 is the same as that of the drum 26.

From the foregoing description the mode of operation of the invention will already be apparent. It may be said, however, that dependent on the direction in which it is intended to act, the mechanism 10 will be 115 mounted on one side or the other of the machine frame, being always mounted on the advancing side of the latter and with the flexible feeding member engaging element 54 in the plane of the sheaves 4 and 6 or 4^a 120 and 6^a. When sumping is completed, the brake band 46 is slackened and the chain 3 and the cable 27 are led up to the top of the pitch and preferably fastened to separate jacks. The cable 27 should have a little slack in 125 it when cutting commences. The engagement of the links of chain 3 with the driving wheel 54 having been checked up, feeding and cutting may be begun. The machine will then move up the incline along 130

the chain 3 and as the sprocket 54 runs along the chain it will rotate the drum and wind in the cable 27. Should the feed chain break or its jack slip or any other part of the feeding mechanism break, the cable 27 will support the machine, for though the pawl slips freely over the ratchet teeth during winding in, opposite rotation of the drum is impossible. When the top of the pitch is reached, the machine may be lowered by slackening the brake band. In cutting in the opposite direction the positions of the pawls are changed by the handle 43. Member 54 may have link pockets if desired.

While I have in this application specifically described one form which my invention may assume in practice, it will be understood that this form of the same is shown for purposes of illustration and that the invention may be modified and embodied in various other forms without departing from its spirit or the scope of the appended claims.

25 What I claim as new and desire to secure by Letters Patent is:

1. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure of any part of its feeding mechanism including a safety flexible connection, winding means associated therewith, and means cooperating with said winding means to maintain the free length of the safety flexible connection substantially the same as the free length of the advance feeding portion.

2. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure of any part of its feeding mechanism including a safety flexible connection, winding means associated therewith, and means cooperating with said winding means and operated by said feeding mechanism to maintain the free length of the safety flexible connection substantially the same as the free length of the advance feeding portion.

3. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on

failure of its feeding mechanism including a safety flexible connection, winding means associated therewith, and means cooperating with said winding means and operated by said flexible feeding means to maintain the free length of the safety flexible connection substantially the same as the free length of the advance feeding portion.

4. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure of its feeding mechanism including a safety flexible connection, winding means associated therewith, and means cooperating with said winding means and operated by said advance feeding portion to maintain the free length of the safety flexible connection substantially the same as the free length of the advance feeding portion.

5. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure of any part of its feeding mechanism including a safety flexible connection, a drum associated therewith, and means cooperating with said drum to maintain the free length of the safety flexible connection substantially the same as the free length of the advance feeding portion.

6. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure of any part of its feeding mechanism including a safety flexible connection, winding means associated therewith, and friction controlled means cooperating with said winding means to maintain the free length of the safety flexible connection substantially the same as the free length of the advance feeding portion but operative on release of its frictional control to permit increase in the length of said connection.

7. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure

of any part of its feeding mechanism including a safety flexible connection, winding means associated therewith, and means cooperating with said winding means to maintain the free length of the safety flexible connection substantially the same as the free length of the advance feeding portion, said means having associated therewith ratchet means for preventing reverse rotation of said winding means.

8. In a mining apparatus, a mining machine having feeding mechanism including flexible feeding means and feed operating means cooperating therewith and adapted to shorten an advance feeding portion to move the machine towards a point in advance thereof, and a safety device operative to support the machine on failure of its feeding mechanism including a safety flexible connection, winding means associated therewith, and means cooperating with said winding means to maintain the free length of the safety flexible connection substantially the same as the free length of the advance feeding portion, said means having associated therewith friction controlled ratchet means for preventing reverse rotation of said winding means.

9. In a mining apparatus, a mining machine having feeding mechanism including flexible feeding means and feed operating means cooperating therewith and adapted to shorten an advance feeding portion to move the machine towards a point in advance thereof, and a safety device on the machine operative to support the machine on failure of any part of its feeding mechanism including a safety flexible connection, winding means associated therewith, and means cooperating with said winding means to maintain the free length of the safety flexible connection substantially the same as the free length of the advance feeding portion, said means having associated therewith reversible ratchet means for preventing reverse rotation of said winding means.

10. In a mining apparatus, a mining machine having feeding mechanism including flexible feeding means and feed operating means cooperating therewith and adapted to shorten an advance feeding portion to move the machine towards a point in advance thereof, and a safety device operative to support the machine on failure of its feeding mechanism including a safety flexible connection, winding means associated therewith, and means cooperating with said winding means to maintain the free length of the safety flexible connection substantially the same as the free length of the advance feeding portion, said means having associated therewith reversible friction controlled ratchet means for preventing reverse rotation of said winding means.

11. In an apparatus of the character described, a support, a rotatable shaft journaled thereon, driving means for said shaft adapted for actuation by the feeding mechanism of a mining machine, a winding member separate from the feeding mechanism and rotatable by said shaft, and ratchet and pawl mechanism comprising elements rotatable relative to each other, one of said elements being operatively connected with one of said rotatable members and the other normally held stationary.

12. In an apparatus of the character described, a support, a rotatable shaft member journaled thereon, driving means for said shaft member adapted for actuation by the feeding mechanism of a mining machine, a winding member separate from the feeding mechanism and concentric with and rotatable by said shaft member, and ratchet and pawl mechanism comprising elements rotatable relative to each other, one of said elements being operatively connected with one of said rotatable members and the other normally held stationary.

13. In an apparatus of the character described, a support, a rotatable shaft journaled thereon, driving means for said shaft adapted for actuation by the feeding mechanism of a mining machine, a winding member separate from the feeding mechanism and rotatable by said shaft, and ratchet and pawl mechanism comprising elements rotatable relative to each other, one of said elements being operatively connected with said winding member and the other normally held stationary.

14. In an apparatus of the character described, a support, a rotatable shaft journaled thereon, driving means for said shaft adapted for actuation by the feeding mechanism of a mining machine, a winding member separate from the feeding mechanism and rotatable by said shaft, and ratchet and pawl mechanism comprising elements rotatable relative to each other, one of said elements being operatively connected to and concentric with said winding member and the other normally held stationary.

15. In an apparatus of the character described, a support, a rotatable shaft member journaled thereon, driving means for said shaft member adapted for actuation by the feeding mechanism of a mining machine, a winding member rotatable by said shaft member, and ratchet and pawl mechanism comprising elements rotatable relative to each other, one of said elements being operatively connected with one of said rotatable members and friction means for holding the other stationary.

16. In an apparatus of the character described, a support, a rotatable shaft journaled thereon, driving means for said shaft adapted for actuation by the feeding mech-

anism of a mining machine, a winding member rotatable by said shaft, and ratchet and pawl mechanism comprising elements rotatable relative to each other, said ratchet element having frictional controlling means and said pawl element being mounted for rotation with said winding means.

17. In an apparatus of the character described, a support, a rotatable shaft journaled thereon, driving means for said shaft adapted for actuation by the feeding mechanism of a mining machine, a winding member rotatable by said shaft, and ratchet and pawl mechanism comprising elements rotatable relative to each other, said ratchet element having frictional controlling means and said pawl element being mounted for rotation with said shaft.

18. In an apparatus of the character described, a support, a rotatable shaft journaled thereon, driving means for said shaft adapted for actuation by the feeding mechanism of a mining machine, a winding member separate from the feeding mechanism and rotatable by said shaft, and ratchet and pawl mechanism comprising elements rotatable relative to each other, said ratchet and pawl mechanism including pawl means rotatable with said shaft.

19. In an apparatus of the character described, a support, a rotatable shaft journaled thereon, driving means for said shaft adapted for actuation by the feeding mechanism of a mining machine, a winding member separate from the feeding mechanism and rotatable by said shaft, and ratchet and pawl mechanism comprising elements rotatable relative to each other, said ratchet and pawl mechanism including pawl means rotatable with said shaft and means for rendering said pawl means reversely operative carried by and rotatable relative to said shaft.

20. In an apparatus of the character described, a support, a rotatable shaft jour-

naled thereon, driving means for said shaft adapted for actuation by the feeding mechanism of a mining machine, a winding member separate from the feeding mechanism and rotatable by said shaft, and ratchet and pawl mechanism comprising elements rotatable relative to each other, said ratchet and pawl mechanism including pawl means rotatable with said shaft, means for rendering said pawl means reversely operative carried by and rotatable relative to said shaft, and means for securing said last mentioned means to said shaft.

21. In a mining apparatus, a mining machine having feeding mechanism including flexible feeding means and a rotatable member adapted to draw in said flexible feeding means, and a safety device on the machine operative to support the machine upon failure of any part of the feeding mechanism comprising a flexible safety member and a rotatable member separate from said rotatable feeding member for drawing in said flexible safety member.

22. In a mining apparatus, a machine having feeding mechanism including flexible feeding means, and feed operating means cooperating therewith and adapted to shorten an advance feeding portion to move the machine towards a point in advance thereof, and a safety device on the machine operative to support the machine on failure of its feeding mechanism including a safety flexible connection, winding means separate from the feed operating means associated with said safety connection, means cooperating with said winding means to rotate the same in one direction to maintain the free length of said safety flexible connection substantially the same as the free length of the advance feeding portion, and means for preventing rotation of said winding means in the opposite direction.

In testimony whereof I affix my signature.
MORRIS P. HOLMES.
